(57) **CLAIM**

The ornamental design for an insulated bottle, as shown and described.

DESCRIPTION

FIG. 1 is a top, front and right side perspective view of an insulated bottle, showing my new design;
FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof, with its handle in an upright state;

FIG. 10 is a perspective view thereof, with its spoon clasp in an open state; and

FIG. 11 is an exploded view thereof, with its lid in an open state; and,

FIG. 12 is an enlarged view of a portion of FIG. 2.

The broken lines in the drawings show a portion of the insulated bottle that forms no part of the claimed design. The long dash-short dash lines surround the enlarged view and form no part of the claimed design. The dot-dash broken lines show a boundary of the claim and form no part of the claimed design.
